UNITED STATES PATENT OFFICE.

HARRY SWINGLEHURST, OF BOSTON, MASSACHUSETTS, ASSIGNOR, BY MESNE ASSIGNMENTS, TO SCOTT & WILLIAMS, INCORPORATED, A CORPORATION OF MASSACHUSETTS.

NEEDLE-LEVELING DEVICE FOR CIRCULAR-KNITTING MACHINES.

1,234,417.

Specification of Letters Patent. Patented July 24, 1917.

Application filed October 5, 1911. Serial No. 653,003.

To all whom it may concern:

Be it known that I, HARRY SWINGLEHURST, a citizen of the United States, and a resident of Boston, in the county of Suffolk and State of Massachusetts, have invented an Improvement in Needle-Leveling Devices for Circular-Knitting Machines, of which the following description, in connection with the accompanying drawings, is a specification, like characters on the drawings representing like parts.

This invention relates to needle leveling devices for circular knitting machines and more particularly to circular knitting machines having independently operated latch needles.

In order that the principle of the invention may be readily understood, I have disclosed a single embodiment thereof in the accompanying drawings, wherein—

Figure 1 is a side elevation of those parts of the knitting machine to which my invention more particularly pertains;

Fig. 2 is a transverse section on the line 25 2—2 of Fig. 1;

Fig. 3 is a plan view of the mechanism shown in Fig. 1 with the knitting cam in operative position;

Fig. 4 is a detail in vertical section upon 30 an enlarged scale showing the two positions of the knitting cam; and

Fig. 5 is a detail in plan view of a portion of the mechanism shown in Fig. 3 and upon a larger scale;

Fig. 6 is a face view of the stitch and leveling cams.

The invention herein disclosed is adapted for use in connection with many different types of knitting machines, but I have chosen to illustrate the same as applied to a circular knitting machine of the type shown in the U. S. Patent to George D. Mayo, No. 726,178, dated April 21, 1903.

The machine shown in said patent is provided with a single knitting cam and an important object of my invention is to provide suitable means for holding said cam out of engagement with the heels of the needles during the transfer operation. It is to be understood, however, that my invention is not limited to knitting cam mechanism of said single cam type.

Referring more particularly to the drawings, the needle cylinder is indicated at 1,

it being of any suitable type, for example, 55 that shown in the said Mayo patent. Preferably, however, rotation is imparted thereto in the knitting operation rather than to the cam ring, but my invention is not limited to knitting machines of the rotary needle 60 cylinder type. Circumferentially within the needle cylinder is the carrier cylinder 2 of any suitable construction and exterior thereto is the bed plate 3 having a depending tubular bearing 4. Surrounding the 65 needle cylinder is a suitable cam ring 5, preferably having a single knitting cam 6 of the type shown in said Mayo patent. At the upper end of said needle cylinder I preferably provide a suitable sinker cylinder and sinker cam carrier not herein necessary fully to describe. The machine is also provided with suitable picker mechanism co-acting with the needles during the formation of the heels and toes for narrowing 75 and widening, such, for example, as that shown in said Mayo patent.

The latch ring, opener, or guard device 80 preferably formed as a complete circle, is indicated at 7, it being herein provided with an arm 8 pivoted at 9 upon a post 10 rising from the bed plate 3. Opposite the arm 8, the latch ring 7 is provided with a projection 11 adapted to rest upon and if desired to interlock with the post 12 rising from 85 the bed plate 3 preferably opposite the post 10. The latch ring 7 is adapted to be swung upon its pivot 9 into an elevated position as shown in dotted lines, Fig. 1, to permit the application of the transfer cup in effecting the transfer of the rib top to the needles. Any other suitable construction of latch ring or equivalent opener or guard device 90 for the needle latches may be employed.

The knitting cam 6 is radially movable 95 from its active or knitting position into an outer inactive position to facilitate transfer of work and for other purposes, and in this respect is generally similar to the knitting cam of said Mayo patent, wherein there 100 is disclosed lever mechanism by which said cam may be withdrawn or removed from the path of the needle heels when desired and without necessarily changing the direction of relative movement between the 105 needles and cam to avoid depressing the needles and to permit the said needles to be raised into one and the same elevated plane

for the transfer of the work. Heretofore, so far as I am aware, it has been necessary to hold the knitting cam manually in its out or inactive position during the transfer of the work or to let the cam be forced radially inward against the needles. I have found both of these practices to be objectionable and have devised means for holding or positively locking the said cam in its out or inactive position. I have also provided means, preferably automatic, for restoring the cam to its active position after or upon the completion of the transfer. As herein shown, I have operatively connected the latch ring with the knitting cam holding or locking means so that upon the completion of the transfer and the return of the latch ring to its active position, the knitting cam may be automatically restored to its active position. Within the scope of my invention, however, the knitting cam may be restored manually or otherwise to its active position.

Upon a bracket 13 upon the bed plate I 25 pivot at 14 a latch 15, the inner end whereof is adapted to engage a lip 16 secured to or formed upon the outer surface of the knitting cam 6. The radial position of said latch 15 is such that when it is engaged with the lip 16, the knitting cam is held in inactive position out of contact with the heels of all the needles. A coiled spring 17 is employed tending to force the inner end or head of the latch 15 downwardly.

Any suitable means may be provided to move the knitting cam 6 radially. For the purpose, I have herein provided a lever 18 pivoted at 19 upon the cam ring or carrier and having an inner slotted end 20 engaging 40 with said knitting cam. By inward pressure upon the outer end 21 of the lever 18, the knitting cam is moved into its outer or inactive position. A spring 22 is provided, tending normally to restore the knitting 45 cam to active position. Pivoted co-axially with the latch ring 9 is a lever 23 having a short arm 24 provided with a pin or lug 25 adapted to take under the arm 8 of the latch ring 7. The opposite and longer arm 26 of said lever 23 has pivoted to its lower end a rod or member 27 having, as shown in Fig. 2, an inner, preferably beveled end 28 adapted to reciprocate in an opening 29 near the lower edge of the bearing 4 of the bed plate 50 3 and to take under the lower edge of the needle cylinder 1, so as to hold the same in an elevated position which is preferably an intermediate or tuck position to which the cylinder is lowered after it has been elevated in any suitable manner for the transfer of work, for instance as fully set forth in the co-pending application of Joseph H. Zens, Serial No. 636,302, (Patent No. 1,084,778 dated January 20, 1914).

65 A spring 30 is provided tending normally

to move the rod or member 27 inward and to hold the pin or lug 25 in engagement with the arm 8 of the latch ring 7.

In order automatically to control the latch 15, I have in this embodiment of my invention provided the lever arm 26 with a lug or projection 31 having therein a set screw 32 adapted to take against the outer end of the latch 15.

Viewing Fig. 1, it will be evident that 75 when the latch ring is down in active position, the set screw 32 engages the latch 15, thereby holding its inner end in elevated position out of the path of engagement with the lip 16 of the knitting cam 6. When, however, the latch ring 7 has been elevated for the transfer of work and the needle cylinder 1 has been elevated to permit the inward movement of the rod 27, then the arm 26 of the lever 23 is moved radially inward by 85 the spring 30, thus elevating the set screw 32 from engagement with the latch 15, and thereby permitting said latch to engage the lip 16 of the knitting cam 6, when the latter has been moved into its inactive position 90 by the lever 18.

When the latch ring is returned to active position, the lever 23 is thereby shifted to elevate the latch 15 from engagement with the knitting cam, thus permitting the latter 95 to be returned to active position. The described movement of the lever 23 also withdraws the rod or member 27 from under the needle cylinder, thus permitting the latter to descend to knitting position.

I provide a leveling cam to keep the inactive needles constantly at their proper level. In order that such cam may be moved when desired into inactive position, I mount the same upon the stitch cam, as by screw 35. 100 In Figs. 1, 4, and 6 said cam is represented at 33, providing a path 34 for the heels of the needles between its lower apex and the top of the stitch cam.

Having thus described one illustrative embodiment of my invention, I desire it to be understood that although specific terms are employed, they are used in a generic and descriptive sense and not for purposes of limitation, the scope of the invention being set 110 forth in the following claims.

Claims:

1. Knitting mechanism comprising in combination a cam carrier having a knitting cam movable into and out of operative position, a latch ring or opener, means for retaining said cam in an inoperative position, and means co-operating with said latch ring or opener adapted to cause said retaining means to release said cam.

2. Knitting mechanism comprising in combination a cam carrier having a knitting cam movable into and out of operative position, a latch ring or opener, and means under the control of the latch ring or opener 125 130

to retain said knitting cam in inoperative position.

3. Knitting mechanism comprising in combination a needle cylinder positionable at different elevations, a cam carrier having a knitting cam movable into and out of operative position, and means co-operating to support the needle cylinder in elevated position and also to retain said cam in inoperative position, said means being positioned in the path of and adapted to be actuated by movement of the latch ring or opener.

4. Knitting mechanism comprising in combination a cam carrier having a radially movable knitting cam, a latch to hold it in inoperative position, a latch ring, and means under the control of said latch ring to render said latch active or inactive.

5. Knitting mechanism comprising in combination a cam carrier having a knitting cam movable into and out of the path of the needles, retaining means to hold said cam in inoperative position, a movable latch ring or opener, and means controlled by said latch ring or opener to render said retaining means active.

6. Knitting mechanism comprising in combination a cam carrier having a knitting cam movable into operative and inoperative positions, a latch guard device movable into and out of operative position, retaining means to hold said knitting cam in inoperative position, and means controlled by movement of said latch guard device into operative position to release the knitting cam from said retaining means.

7. Knitting mechanism comprising in combination a cam carrier having a knitting cam movable into and out of operative position, retaining means to hold said cam in inoperative position, a latch ring or opener movable into active and inactive positions, and means acting substantially simultaneously with the movement of the latch ring into operative position to release said knitting cam from said retaining means.

8. Knitting mechanism comprising in combination a cam carrier having a knitting cam movable into operative and inoperative positions, a latch to hold said cam in inoperative position, a pivoted latch ring and a movable member acted upon by movement of the latch ring to render said latch active or inactive.

9. Knitting mechanism comprising knitting needles and a cam carrier having a stitch cam movable into and out of contact with said needles, and a leveling cam, said stitch and leveling cams extending on each side of and defining a free level for needles carried above said stitch cam, said leveling cam being fixed relatively to said stitch cam, and movable therewith into operative and inoperative positions.

In testimony whereof, I have signed my name to this specification, in the presence of two subscribing witnesses.

HARRY SWINGLEHURST.
